ROTARY HOOK MECHANISM FOR SEWING MACHINES

Walter Myers, Bridgeport, Conn., assignor to The Singer Manufacturing Company, Elizabeth, N. J., a corporation of New Jersey

Application August 13, 1942, Serial No. 454,655

10 Claims. (Cl. 112—256)

This invention relates to lubricating devices for the thread-carrier raceways of rotary loop-takers for sewing machines and, more particularly, for the thread-carrier raceways of vertical-axis loop-takers of the rotary hook type.

The present invention aims to provide simple and efficient means for delivering lubricant to the raceway of a rotary loop-taker. A more specific object of the invention is to provide loop-taker raceway lubricating means functioning to minimize overheating of the loop-taker and of the journaling means in the vicinity of the loop-taker, thereby to increase the life of the loop-taker. Other objects of the invention will be apparent from the following description and claims.

The invention consists in the lubricant collecting and delivering means hereinafter described in connection with the accompanying drawings, which illustrate two forms of the improvement and in which:

Fig. 1 represents an enlarged vertical section, partly in front elevation, of a portion of a sewing machine containing the improved loop-taker mechanism. Fig. 2 represents a horizontal section of the loop-taker hub shown in Fig. 1, the section being taken substantially on the line 2—2 of Fig. 1. Fig. 3 represents an enlarged fragmental view, similar to Fig. 1 and showing a modified form of lubricant collecting and distributing means. Fig. 4 represents a horizontal section of the hub of the loop-taker illustrated in Fig. 3; the section being taken substantially on the line 4—4 of Fig. 3.

The sewing machine which is in part illustrated in the drawings has the usual bed 1 provided with the work-supporting slide-plates 2 and 3, and with a throat-plate 4 disposed between said slide-plates.

Depending from the bed 1 is a lug 5 provided with a horizontally apertured bearing-bushing 6. A loop-taker and feed-actuating shaft 7 is rotatably journaled in the bearing-bushing 6 to extend horizontally lengthwise of the bed 1. Carried by the rotary shaft 7 is a feed-lift eccentric 8 engaged by a feed-bar 9 provided with a work-advancing feed-dog 10. The feed-dog 10 operates through feed-slots 11 provided in the throat-plate 4 and is actuated to cooperate, in a conventional manner, with one or more endwise reciprocatory and laterally vibratory thread-carrying needles 12 in advancing the work. The feed-dog 10 is opposed by the usual spring-depressed presser-foot 13.

Complemental to the right hand needle 12, in the formation of lock-stitches, is a rotary loop-taker 14 of the vertical-axis rotary hook type, i. e., of the type in which the hook rotates about an axis substantially normal to the work-support. The rotary hook 14 has a cup-shaped body including a bottom wall 15 and a generally cylindrical side wall 16.

10 Journaled in a raceway 16' provided in the side wall 16 of the rotary hook body is a thread-carrier 17 restrained against rotation with the rotary hook. The bottom wall 15 of the rotary hook is externally provided with a depending annular flange 18 concentric with a vertically disposed rotary hook shaft 19 of which the upper end is preferably integral with the hook. The radius of the hub-flange 18 is preferably substantially shorter than that of the side wall 16 of the rotary hook. The hook-shaft 19 has a longitudinal bore 20 which extends through the bottom wall 15 and its flange 18 of the hook-body, and the upper end of said bore terminates in a countersink 21 in the inner face of the hook bottom wall 15. The hook-shaft bore 20 opens into an enlarged counterbore 22 formed in the lower portion of the hook-shaft 19. Disposed in said counter-bore 22 is the reduced stem 23 of an eccentric 24 held in engagement with the lower end of the shaft 19 by a screw 25. To this end, the screw 25 is passed downwardly through the bore 20 of the hook-shaft and is threaded into the stem 23 of the eccentric 24; the head 25' of said screw being disposed in the countersink 21 of the hook-body. The eccentric 24 is locked to the hook-shaft 19 for rotation in timed relation therewith by means of a pin 26 extending transversely through the stem 23 of the eccentric and entering suitable notches, as 27, in the lower end of the hook-shaft.

45 The hook-shaft 19 is rotatably supported by a bracket or hook-saddle 28 which is disposed below the work-support of the machine and, as usual, is in part supported by a reduced portion 6' of the bearing-bushing 6. The bracket 28 is cut away to provide a gear-clearance cavity 29 between vertically spaced walls 30 and 31. The upper wall 30 of the bracket has a vertical shaft-clearance opening 32; said wall 30 being provided in its upper face with an annular cavity 33; said cavity forming an oil-cup into which the hub-flange 18 of the rotary hook depends. The wall 30 is provided in its lower face with a ball-bearing cavity 34. The hook-shaft 19 is slightly 50 enlarged, adjacent the bottom wall 15 of the hook

to form a shoulder 19 resting upon the bottom wall of the cavity 33. The lower wall 31 of the bracket 28 is likewise provided with an annular opening 35 which is coaxial with and is, in the present case, diametrically of substantially the same size as the lower cavity 34 of the upper wall. The lower portion of the opening 35 of the lower wall 31 is enlarged to provide a threaded counterbore 36.

Detachably secured by a screw 37 upon the hook-shaft 19, intermediate the ends thereof, is the hub 38 of a spiral pinion-gear 39. The hub 38 of the pinion-gear comprises, in effect, a tubular sleeve having the pinion-gear teeth disposed medianly between the opposite ends of the sleeve. The hub-sleeve 38 has diametrically reduced end-extensions 40 and 41, upon each of which is force-fitted the inner race-ring of a ball-bearing 42. The outer race-ring of the upper ball-bearing 42 is slip fitted into the ball-bearing cavity 34 in the upper bracket-wall 30, and the outer race-ring of the lower ball-bearing 42 is similarly fitted into the opening 35 of the lower bracket-wall 31. The outer race-ring of the lower ball-bearing 42 is circumferentially grooved to receive a conventional split abutment-ring 43 adapted to engage the bracket-shoulder formed by counterboring the lower bracket-wall opening 35. The assembly unit, comprising the pinion-sleeve 38 and the ball-bearings carried thereby, is vertically positioned in the bracket 28 by a screw-plug 45 threaded into the counterbore 36 of the bracket-wall 31 to hold the abutment-ring 43 in engagement with the bracket-shoulder 44.

The pinion-gear 39 is engaged, in the usual manner, by a spiral-gear having its hub 46 suitably secured upon the shaft 7, the ratio of said gears being such that the hook-shaft 19 rotates twice for each rotation of its driving shaft 7. The bracket-cavity 29, in which the hook-shaft driving gears are disposed, is closed by a detachable end-closure plate 47 disposed adjacent the feed-bar 9.

As more fully described in my prior Patent No. 2,236,830, April 1, 1941, the eccentric 24 engages the fork of a crank-arm 48 carried by the lower end of a vertically disposed rock-shaft 49. The rock-shaft 49 is journaled eccentrically in a bushing 50 secured for turning adjustment in the bracket 28 by a screw 51. At its upper end, the rock-shaft 49 carries escapement-fingers, as 52, adapted to enter apertures, as 53, provided in the thread-carrier 17, thereby to restrain the thread-carrier against rotation with the rotary hook. Detachably secured upon the bottom wall of the supporting bracket 28 is a dished closure-plate 54 which houses the hook-shaft eccentric 24 and the crank-arm 48 actuated thereby, said closure-plate also functioning as an oil-holding reservoir.

The present invention resides more particularly in supplying lubricant to the thread-carrier raceway of the rotary hook. In the form of the improvement illustrated in Figs. 1 and 2 of the drawings, the upper wall 30 of the bracket 28 is provided with a horizontal inlet-aperture 55 connected, in any suitable or preferred manner, to a lubricant supply reservoir (not shown) which is disposed above the level of the hook and is manually regulatable to control the quantity of lubricant gravitationally delivered to the aperture 55. However, any other suitable lubricant supplying means may be employed. The aperture 55 of the wall 30 is connected by a short duct 56 with the upper face of the bottom wall of the

oil-cup cavity 33, at a point in said face within the area circumscribed by the hub-flange 18 of the rotary hook.

The hub-flange 18 depends into close proximity to the bottom wall of the oil-cup cavity 33 and is encircled by the side wall of said cavity; said side wall of the cavity being disposed in close proximity to the flange 18. The circumferentially inner face 57 of the flange 18 is preferably undercut and is therefore outwardly inclined upwardly. Disposed within the flange 18, for rotation with the hook, is a lubricant-absorbent substance as, for example, a felt-ring 58 which is preferably in wiping contact with the bottom wall of the cavity 33. Leading from the upper edge of the inclined flange-face 57 is an outwardly and upwardly inclined duct 60 connected to another duct 61 terminating in the thread-carrier raceway 16 of the rotary hook; said ducts 60, 61 being provided in the bottom and side walls of the hook.

In the operation of the machine, the lubricant supplied to the oil-cup cavity 33, through the bracket-wall ducts 55 and 56, is picked up by the lubricant-absorbent material 58 which rotates with the rotary hook. The picked-up lubricant is thrown centrifugally outwardly and is caught by the undercut flange-face 57; said face directing the lubricant upwardly toward the upper edge thereof. Lubricant is thereby delivered to the rotary hook duct 60, through which duct the lubricant passes centrifugally to the duct 61 and thence to the rotary hook raceway. Should excess lubricant be inadvertently delivered through the ducts 55, 56 when the machine is idle, the lubricant is free to drain downwardly through the shaft-clearance opening 32 and into the gear-cavity of the bracket 28.

It will be noted from Fig. 1 of the drawings that the bottom wall 15 of the hook is in close proximity to but is spaced slightly from the upper face of the bracket-wall 30 outwardly of the hub-flange 18. It will be further noted that the hub-flange 18 has a conical outer face, whereby the inner and outer faces of the flange are upwardly convergent and said flange functions as an oil-sling. As the lubricant is supplied through the duct 56 to the oil-cup cavity 33 at a point within the hub-flange 18 of the rotary hook, the oil-sling action of the outer face of said flange 18 in no way interferes with the delivery of lubricant to the inner face 57 of the hub-flange 18.

In the modification illustrated in Figs. 3 and 4 of the drawings, the upper wall 30 of the bracket 28 is provided with a ball-bearing opening 62 which is counterbored from the upper face of said wall 30 to form a clearance-opening 63 which is diametrically very slightly larger than the rotary hook hub-flange 18 embraced by the wall of said opening 63.

Seated in the opening 63, in vertically spaced relation to the ball-bearing 42 and so as to be restrained against rotation with the rotary hook 14, is a hardened insert 64 having a central shaft-clearance opening 65; said insert 64 having a central flange 66 extending upwardly into close proximity to the bottom wall 15 of the rotary hook. The thickness of the insert 64 is substantially less than the depth of the counterbore-opening 63, whereby the wall of said opening 63 and the flanged insert 64 together form a lubricant-collection cavity. The insert 64 has a horizontal duct 67 aligned with the bracket inlet-aperture 55 described in connection with

Fig. 1; said duct 67 being connected by a vertical aperture 68 with the upper face of the insert 64, at a point in said face within the area circumscribed by the hub-flange 18 of the rotary hook.

The lower face of the bottom wall 15 of the rotary hook and the upper face of the insert 64 are held spaced from each other by a plurality of thrust-bearing and lubricant-distributing balls 69. The balls 69 are held separated from each other by a cage-disk 70 provided with a plurality of peripheral ball-receiving notches 71 which permit radial movement of the balls 69, under centrifugal force, into engagement with the hub-flange 18 of the rotary hook. The cage-disk 70 has a central aperture to embrace the insert-flange 66 and to provide for turning movement of said disk about said flange 66.

Lubricant supplied through the wall-duct 55 and the insert-ducts 67 and 68 to the upper face of the insert 64 is picked up by the balls 69; in the operation of the machine, and is delivered by the rotating balls 69 to the inner face 57 of the hub-flange 18, from which the lubricant is supplied to the hook raceway in the same manner as before described.

The balls 69 also function as an anti-friction support for the rotary hook 14 in a form of construction providing for convenient replacement of the rotary hook.

Having thus set forth the nature of the invention, what I claim herein is:

1. In a sewing machine, in combination, a rotary hook having a body providing a bottom wall and a cylindrical side wall; said side wall being provided with a thread-carrier raceway, and said bottom wall being externally provided with an annular flange having an undercut inner side face, a thread-carrier journaled in said raceway and restrained against rotation with said hook; a lubricant-collecting cup having a side wall encircling said flange in close proximity thereto; a lubricant-supply conduit opening into said cup at a point within an area circumscribed by said flange; and lubricant conducting connections between said undercut face of the flange and said raceway.

2. In a sewing machine, in combination, a rotary hook having a body providing a bottom wall and a cylindrical side wall; said side wall being provided with a thread-carrier raceway, and said bottom wall being externally provided with a depending annular flange having an inner side face inclined outwardly in an upward direction; means for rotating said hook about a vertical axis; a thread-carrier journaled in said raceway and restrained against rotation with said hook; a lubricant-collecting cup having a bottom wall disposed in close proximity to and having a side wall encircling said flange; lubricant-conducting connections with the upper face of the bottom wall of said cup at a point within an area of said face circumscribed by said flange; and lubricant-conducting connections between said inner face of the hook-flange and said raceway.

3. In a sewing machine, in combination, a rotary hook disposed for rotation about a vertical axis and having a body providing a bottom wall and a cylindrical side wall; said side wall being provided with a thread-carrier raceway, and said bottom wall having a depending circular flange formed with upwardly convergent opposed side faces; means for rotating said hook; a thread-carrier journaled in said raceway and restrained

against rotation with said hook; a rotary hook supporting bracket provided with an upwardly open lubricant-collection cavity; said cavity having a bottom wall disposed in close proximity to said flange, and said cavity having a side wall encircling said flange and underlying said bottom wall of the rotary hook in close proximity thereto; a lubricant-inlet conduit connected with said cavity in an area circumscribed by said flange; and a lubricant-conduit connecting the inner face of said flange and said raceway of the rotary hook.

4. In a sewing machine, a supporting bracket provided in its upper face with a lubricant-collecting cavity having a cylindrical side wall and a substantially flat bottom wall formed centrally thereof with a clearance opening; a shaft journaled in said bracket for rotation about a vertical axis and extending through said clearance opening; a rotary hook carried by the upper end of said shaft and having a cylindrical side wall provided with a thread-carrier raceway; said rotary hook having a bottom wall provided with a circular flange spaced from said shaft and depending into said cavity; a thread-carrier journaled in said hook and restrained against rotation therewith; a lubricant-inlet conduit connected with said cavity; a ring of lubricant-conducting material embracing said shaft within said flange, said ring being disposed in contact with the inner face of said flange; and a lubricant-conduit connecting the inner face of said flange with said raceway of the rotary hook.

5. In a sewing machine, in combination, a rotary hook having a body providing a bottom wall and a cylindrical side wall; said side wall being provided with a thread-carrier raceway, and said bottom wall being externally provided with a depending annular flange; means for rotating said hook about a vertical axis; a thread-carrier journaled in said raceway and restrained against rotation with said hook; a lubricant-cup having a bottom wall disposed in close proximity to and having a side wall encircling said flange; a lubricant-supply conduit extending through the bottom wall of said cup and terminating in the upper face of said bottom wall at a point within an area circumscribed by said flange; lubricant-conducting means disposed within said flange for delivering lubricant from said cup to the inner side face of said flange; and lubricant-conducting connections between said inner side face of the hook-flange and said raceway.

6. In a sewing machine, in combination, a rotary hook having a body providing a bottom wall and a cylindrical side wall; said side wall being provided with a thread-carrier raceway; and said bottom wall being externally provided with a depending annular flange; means for rotating said hook about a vertical axis; a thread-carrier journaled in said raceway and restrained against rotation with said hook; a lubricant-cup having a bottom wall disposed in close proximity to and having a side wall encircling said flange; lubricant-conducting connections with said cup; lubricant-conducting means disposed within said flange and rendered effective upon rotation of said hook for delivering lubricant from said cup to the inner side face of said flange; and lubricant-conducting connections between said inner side face of the hook-flange and said raceway.

7. In a sewing machine, in combination, a rotary hook having a body providing a bottom wall and a cylindrical side wall; said side wall being provided with a thread-carrier raceway, and said

bottom wall being externally provided with a depending annular flange; means for rotating said hook about a vertical axis; a thread-carrier journaled in said raceway and restrained against rotation with said hook; a lubricant-cup having a bottom wall disposed in close proximity to and having a side wall encircling said flange; lubricant-conducting connections with said cup; a lubricant-absorbent material disposed within said flange in wiping contact with the bottom wall of said lubricant-cup; and lubricant-conducting connections between the inner side face of the hook-flange and said raceway.

8. In a sewing machine, in combination, a rotary hook having a body providing a bottom wall and a cylindrical side wall; said side wall being provided with a thread-carrier raceway; and said bottom wall being externally provided with a depending annular flange; means for rotating said hook about a vertical axis; a thread-carrier journaled in said raceway and restrained against rotation with said hook; a lubricant-cup having a bottom wall disposed in close proximity to and having a side wall encircling said flange; lubricant-conducting connections with said cup; a plurality of balls disposed within said flange, said balls being movable into engagement with the inner side face of the flange and having rolling contact with the bottom wall of said lubricant-cup; and lubricant-conducting connections between said inner side face of the hook flange and said raceway.

9. In a sewing machine, in combination, a rotary hook having a body providing a bottom wall and a cylindrical side wall; said side wall being provided with a thread-carrier raceway; and said bottom wall being externally provided with a depending annular flange; means for rotating said hook about a vertical axis; a thread-carrier jour-

naled in said raceway and restrained against rotation with said hook; a lubricant-cup having a bottom wall disposed in close proximity to and having a side wall encircling said flange; lubricant-conducting connections with said cup; a plurality of balls disposed within said flange, said balls being movable into engagement with the inner side face of the flange and having rolling contact with the bottom wall of said lubricant-cup; a ball-separating cage disposed within said flange; and lubricant-conducting connections between said inner side face of the hook-flange and said raceway.

10. In a sewing machine, in combination, a vertical-axis rotary hook having a body providing a substantially horizontal bottom wall and a cylindrical side wall; said side wall having a thread-carrier raceway, and said bottom wall having a depending circular flange spaced inwardly from the outer edge of the bottom wall; said flange having an upwardly and outwardly inclined inner face terminating at its upper edge in said bottom wall; a thread-carrier journaled in said raceway and restrained against rotation with said hook; a lubricant-collecting cup having a bottom wall disposed in close proximity to the rim of said flange and having a cylindrical side wall embracing said flange; said side wall of said cup being disposed below and extending into close proximity to said bottom wall of the hook externally of said flange; a lubricant-supply duct terminating in the upper face of the bottom wall of said cup at a point within the area circumscribed by said flange; and said body of the hook having an upwardly and outwardly inclined duct leading from the inner face of said flange and connected with said raceway.

WALTER MYERS
